DESIGN FOR A RADIO RECEIVER CABINET OR THE LIKE

Robert Cooper Scull and Jacques Martial, New York, N. Y., assignors to Electronic Corp. of America, New York, N. Y.

Application July 25, 1945, Serial No. 120,958

Term of patent 3½ years

(Cl. D56—4)

To all whom it may concern:

Be it known that we, Robert Cooper Scull and Jacques Martial, citizens of the United States and residents of the city, county, and State of New York, have invented a new, original, and ornamental Design for a Radio Receiver Cabinet or the like, of which the following is a specification, reference being had to the accompanying drawings, forming part thereof, in which:

Fig. 1 is a front elevational view of a radio receiver cabinet or the like embodying our design.

Fig. 2 is a side elevational view of the same.

Fig. 3 is a section taken along lines 3—3 of Fig. 1.

Fig. 4 is a section taken along lines 4—4 of Fig. 1.

Fig. 5 is a section taken along lines 5—5 of Fig. 1.

Fig. 6 is a section taken along lines 6—6 of Fig. 1.

The characteristic features of our design are shown by means of full lines in the drawings.

We claim:

The ornamental design for a radio receiver cabinet or the like, as shown and described.

ROBERT COOPER SCULL.
JACQUES MARTIAL.
